SWAN NILS TEVANDER, OF MAYWOOD, ILLINOIS.

CAP FOR COVERING THE OPENING ENDS OF JARS, CANS, ETC.

Application filed March 21, 1924. Serial No. 700,775.

My cap relates to the type of caps which are known as screw caps that are held on to and over the nozzles or openings of the jars or cans by threaded portions on the outside of the jars and on the margin or skirt of the caps.

The object of my invention is to produce a cap that will make a tight seal without the use of the gasket used with screw caps when seals are required.

Reference will be had to the accompanying drawing in which Figure 1 is an elevation of the opening end of a jar with my cap applied.

Figure 2 is a vertical section through Figure 1.

Figure 3 is an enlarged section of a portion of the opening of a jar with the caps secured thereon.

I prefer to make my cap having a metal outside portion lined with paper on the inside, the paper being secured to the metal by a special adhesive which has the result of making the paper and metal as it were a unitary composite material acting as what might be termed a one piece article.

In the drawing, 1 indicates the opening end, nose or nozzle of a glass jar, on the outside of which there are the threads 2. 3 indicates the outside or metal portion of my cap and 4 the paper lining of the cap.

In the manufacture of these caps the paper is applied to the metal in large sheets and suitably treated and then these sheets of composite material are stamped out and formed with the corrugations or threads 5 which are adapted to screw onto the threads 2 of the jar. The lower edge of the skirt of my cap is turned over into the hem 6 shown in the enlarged view in Fig. 3, and thus the skirt of this cap is stiffened by this hemming and the hemming has the effect of preventing as it were, any local displacement of the paper lining 4 from the metal on the edge of the cap as the cap is used frequently by being screwed on or off and this hemmed portion is a defense against injury to the paper lining.

In the ordinary use of screw caps for jars in which are carried preserves, fruit and food stuffs of various kinds the old practice is to use a screw cap having a gasket of some inert or non-corrosive material interposed over the end of the nozzle bearing on the point 7 for the sealing or closing

region of the cap. In any case the old system of screw caps relied for the seal to be effected on the top of the nozzle around the annular surface 7.

It frequently occurs that changes of temperature or change in the chemical action of the contents of the jar causes a gaseous pressure to develop on the inside of the jar and this pressure through the spring of the metal around the region indicated by 8 and the screw threads generally results in breaking the seal on the surface 7 and as it were transmits the responsibility of the tight seal on the contact of the threaded portions of the skirt of the cap.

The screw threaded skirt or flange of the cap when made of metal alone does not conform to the surface of the threads of the glass of the jar to make a tight seal for these threads on the jars are never exactly true as they are distorted in the molding and distorted in the vitrifying or annealing of the jars so that when there is pressure developed on the inside of a jar the seal of which is made through a gasket held on at the surface 7 by the screw threaded cap the bulging of the cap surface frequently breaks this seal and the contents of the jar become damaged because of the screw threaded portions of the cap may not be relied upon to furnish a secure seal of themselves.

The paper lining of my cap while it is not supposed to be elastic to any great extent has the effect of making a tight closure on the screw threads upon the commercial jars as ordinarily used when if the metal alone were relied on for this seal there would be frequent cases where the seal would not be effected on the screw threaded surface.

By close examination of Figure 3 it will be noticed that whenever a screw cap of any kind is screwed down firmly causing the top surface of the cap to jam tightly on to the nozzle surface 7 there then takes place a series of small voids indicated by 9, Fig. 3, and any seal that is to be effected on the screw threaded surface is supposed to be accomplished at the point 10. In a metal cap any slight irregularities of the fits along the portions 10 would allow leaks through the screw threaded portions and thus it has been found that ordinary screw caps using gaskets at the top only are not to be relied upon as making a good seal in all cases of their use and a sufficient number of them always

fails so that packers do not rely on screw threaded caps with complete safety for a seal.

With my cap composed of a composite material like metal and paper made as described the paper is the contacting material on all surfaces where the cap touches the jar and thus a more secure seal is obtained in a screw threaded article than has heretofore been obtained with a direct metal contact of the screw threaded portions of the caps.

What I claim is:—

1. A cap of the class described formed of composite sheet material having an outer layer of stronger material and an inner layer of softer material, the cap having a screw-threaded skirt with the lower edge of the stronger material bent inwardly and upwardly to embrace and enclose the lower margin of the softer material so that only the bent edge of the stronger material is exposed downwardly and the softer material is protected against rupture or separation from the outer layer.

2. A cap of the class described formed of composite sheet material having an outer layer of metal and an inner layer of softer

material such as paper, the cap having a screw-threaded skirt entirely composed of the composite material with the lower edge of the metallic outer layer bent inwardly and upwardly to embrace and enclose the lower marginal portion of the softer material so that only the bent edge of the metal is exposed downwardly and the inner layer of softer material is protected against rupture or separation from the outer layer.

3. A cap of the class described formed of composite sheet material having an outer layer of metal and an inner layer of paper or the like adherent thereto, the cap having a screw-threaded skirt embodying both materials throughout with the lower edge of the metal bent inwardly and upwardly to embrace and clamp the lower marginal portion of the paper lining so that only the bent edge of the metal is exposed downwardly and the lining material is protected against rupture or separation from the metal.

Signed at Chicago, in the county of Cook, and State of Illinois, this 28th day of February, 1924.

SWAN NILS TEVANDER.
